RAILWAY DRAFT RIGGING

George E. Dath, Mokena, Ill., assignor to W. H. Miner, Inc., Chicago, Ill., a corporation of Delaware

Application September 11, 1946, Serial No. 696,268

2 Claims. (Cl. 213—22)

1

This invention relates to improvements in railway draft riggings.

One object of the invention is to provide a railway draft rigging comprising a friction shock absorbing mechanism actuated by the usual drawbar to cushion draft shocks, wherein the friction shock absorbing mechanism includes a friction casing or shell buttressed against the usual end sill of the car, and a spring resisted friction clutch telescoped within the casing and actuated by the drawbar, being forced inwardly of the casing in draft by a follower member carried by the drawbar and adapted to shoulder against the casing to limit compression of the friction shock absorbing mechanism.

Other objects of the invention will more clearly appear from the description and claims herein-after following.

In the accompanying drawings forming a part of this specification, Figure 1 is a longitudinal plan view, partly broken away, of the under-frame structure at one end of a railway car, illustrating my improvements in connection therewith. Figure 2 is a central, longitudinal, vertical sectional view of Figure 1, corresponding substantially to the line 2—2 of said figure, showing the drawbar in side elevation. Figure 3 is a transverse, vertical sectional view, corresponding substantially to the line 3—3 of Figure 2, showing the friction casing in elevation. Figure 4 is a rear elevational view of the front stop member, looking toward the left in Figure 2. Figure 5 is a horizontal sectional view, corresponding substantially to the line 5—5 of Figure 2, showing the mechanism fully compressed, the drawbar being shown partly in elevation. Figure 6 is a transverse, vertical sectional view, corresponding substantially to the line 6—6 of Figure 2.

In said drawings, 10 indicates the usual end sill of the underframe structure of a railway car at one end thereof, and 11—11 the draft sills. Spaced inwardly from the end sill 10 is a transverse beam member 12 to which the inner ends of the draft sills are fixed, suitable brackets 13—13 being employed for this purpose. The draft sills 11—11 are of channel-shaped cross section, having top and bottom flanges 14—14. The front ends of the draft sills are supported from a cover plate 15, which is fixed to the top flanges 14—14 of the sills, the plate 15, in turn, being fixed to an inwardly extending top flange 16 on the end sill.

My improvements, as shown in the drawings, comprise broadly a drawbar A; a front stop B; a friction casing C; a wedge D; friction shoes E—E—E; a spring resistance F; a follower G cooperating with the drawbar A and wedge D; guide rods or bars H—H for the follower G; and a supporting bracket J for the friction casing.

The drawbar A is of the type having a coupling hook at the outer end thereof for engagement with the coupling means of an adjacent

car. The drawbar A has an enlarged head 17 at the outer end having the hook formed thereon. The shank 18 of the drawbar A, which shank extends rearwardly from the hook thereof, is of cylindrical cross section, that is, in the form of a cylindrical bar or shaft. A nut 19 is threaded on the rear end of the shank 18. The drawbar is accommodated for lengthwise sliding movement by the front stop B, which is fixed to the rear side of the end sill 10, as herein-after pointed out, and is provided with a forwardly projecting, cylindrical boss 20, which extends through an opening in the end sill. The boss 20 protrudes slightly beyond the front side 15 of the end sill 10 and is provided with a central opening or bore 21 therethrough in which the shank 18 of the drawbar A is slidably guided. Inward movement of the drawbar is positively limited by shouldered engagement of the head 17 thereof with the outer end face of the boss 20.

The guide rods or bars H are arranged at opposite sides of the drawbar A and have their front and rear ends fixed to the end sill 10 and the beam 12, respectively. The guide rods H—H extend through the end sill 10 and the beam 12 and the front and rear ends of each bar are threaded and provided with nuts 22—22 and 22—22 for clamping the bar H in position. The rear end of each bar H is directly fixed to the beam 12 by the clamping nuts 22—22, which engage the front and rear sides of the beam. The front ends of the bars extend through the end sill 10 and laterally projecting, securing ears 23—23 on the front stop B and are held clamped in position by the nuts 22—22 at said front end, which engage, respectively, the outer side of the end sill 10 and the rear sides of the ears 23—23 of the stop member B, thereby also clamping this stop member to the end sill.

As shown in Figures 1, 2, and 5, the friction shock absorbing unit proper, comprising the casing C, wedge block D, shoes E, and spring F is disposed between the draft sills 11—11 of the car in abutment with the front stop B. The shank 18 of the drawbar A extends through this unit and actuates the same in draft action, as hereinafter pointed out.

The friction casing C is in the form of a shell 50 of hexagonal, transverse cross section, open at the rear end and closed at the front end by a transverse wall 24. As shown most clearly in Figure 2, the closed end of the casing C bears on the front stop member B, being seated in a pocket 25 provided in the stop member. The extreme front end of the casing is rounded, as shown, to fit the pocket, which is also rounded, as clearly illustrated in Figure 4. The side walls of the casing, which are indicated by 26, are thickened at the open rear end of the casing, as indicated at 27, and present six flat, interior friction surfaces 28, which converge inwardly of the casing, thereby providing a tapered friction

shell portion at the open end of the casing. At said open end, the casing has three inturned stop lugs 29, said lugs being located at alternate corners of the same.

The wedge D is in the form of a hollow block having three inwardly extending, flat wedge faces 30 arranged symmetrically about the central longitudinal axis of the mechanism. The wedge block D is also provided with three radially projecting lugs 31, which are in longitudinal alignment with the lugs 29 of the casing and are adapted to engage the same to limit outward movement of the wedge block to hold the same assembled with the casing. The wedge block D has a central opening 32 therethrough adapted to accommodate the shank 18 of the drawbar A.

The friction shoes E, which are three in number, are alternated with the lugs 29 of the casing and each shoe has a lengthwise, extending V-shaped friction surface 33 on the outer side engaging with the corresponding friction surface of the casing, the V-shaped surface of each shoe engaging two adjacent surfaces 28-28 of the casing. On the inner side, each shoe has a wedge face 34 engaged by the corresponding wedge face 30 of the block D.

The spring F, which is preferably under initial compression, is disposed within the casing C and comprises inner and outer coils, bearing at their front ends on the end wall 24 of the casing, and having their rear ends bearing, respectively, on the inner end of the wedge block D and the inner ends of the shoes E.

As clearly shown in Figures 1, 2, and 5, the shank 18 of the drawbar A extends through the casing C of the mechanism, the wall 24 being provided with a central opening therethrough to accommodate the shank. The drawbar shank extends through the opening of the wall 24, the inner coil spring, the opening 32 of the wedge block D, and through the follower G which is carried on the drawbar.

The follower G, as most clearly shown in Figures 3, 5, and 6, is in the form of a vertically disposed, transversely extending, relatively heavy plate having a vertically enlarged, central portion 35 and arms 36 laterally extending from opposite ends of said central portion. The outer ends of the arms are slidably guided on the bars H-H, the same being notched at their outer ends, as indicated at 37-37, to engage over said bars. The drawbar shank 18 extends through a central opening 38 in the portion 35 of the follower G and is anchored to the latter by the nut 19. The nut 19 is threaded on the rear end of the shank and abuts the rear side of the follower. The central portion of the follower G bears directly on the outer end of the wedge block D to actuate the latter. As will be evident, the nut 19 provides for adjustment of the follower G on the drawbar to compensate for wear of the parts of the mechanism and maintains the follower in contact with the wedge in the full release position of the mechanism.

In the operation of the mechanism, when a pulling force is applied to the drawbar, the follower G is pulled forwardly therewith, thereby forcing the wedge D inwardly of the casing against the resistance of the inner coil of the spring F. Due to wedging engagement between the wedge and shoes, the shoes are spread apart and forced against the friction surfaces of the casing and carried inwardly along said surfaces, resisted by the outer coil of the spring F. The resultant combined spring and friction resistance produced by this action provides the desired high

shock absorbing capacity. Compression of the mechanism is positively limited by engagement of the follower G with the rear end of the casing C, as shown in Figure 5, thus preventing the wedge D from being drawn too far into the casing by the drawbar and protecting the spring F against undue compression. When the actuating force is reduced, the spring F restores all of the parts to the normal position shown in Figures 1 and 2, outward movement of the wedge being limited by engagement of the lugs 31 thereof with the lugs 29 of the casing A.

I claim:

1. In a draft rigging for a railway car having a transverse end sill and a transverse beam rearwardly of said end sill, the combination with a front stop member on the inner side of said end sill; of a friction casing open at its rear end and closed at its front end and having said front end in engagement with the front stop; rigidly mounted guide bars at opposite sides of said casing having their rear ends fixed to said transverse beam and their front ends secured to said end sill and front stop member; a transversely disposed follower rearwardly of said casing, said follower extending from one guide bar to the other and being slidably supported on said bars; a plurality of friction shoes slidably telescoped within the rear end of the casing; a wedge block 15 in engagement with the shoes and having its rear end bearing on said follower; spring means within the casing yieldingly resisting inward movement of the wedge and shoes; and a drawbar extending through said end sill, casing, spring means, wedge block, and follower, said drawbar having shouldered engagement with said follower to pull the same forwardly therewith in draft.

2. In a draft rigging for a railway car having a transverse end sill and a transverse beam rearwardly of said end sill, the combination with a front stop member on the inner side of said sill; of a friction casing open at its rear end and closed at its front end and having said front end in engagement with the front stop; rigidly mounted guide bars at opposite sides of said casing having their rear ends fixed to said transverse beam and their front ends secured to said end sill; an elongated, transversely disposed follower rearwardly of said casing, said follower extending from one guide bar to the other and having its opposite ends provided with laterally outwardly opening notches engaged over said guide bars to slidably support said follower for lengthwise movement on said bars; a plurality of friction shoes slidably telescoped within the open end of the casing; a wedge block in wedging engagement with the shoes and having its rear end bearing on said follower; spring means within the casing yieldingly resisting inward movement of the wedge block and shoes; and a drawbar extending through said end sill, spring means, wedge block, and follower, said drawbar having shouldered engagement with said follower to pull the same forwardly in draft.

GEORGE E. DATH.
